CLAIM

The ornamental design for a portable air neck traction device for orthopedic purpose, as shown and described.

DESCRIPTION

FIG. 1 is a front perspective view of a portable air neck traction device for orthopedic purpose;

FIG. 2 is a front elevation view of the portable air neck traction device for orthopedic purpose of FIG. 1;

FIG. 3 is a rear elevation view of the portable air neck traction device for orthopedic purpose of FIG. 1;

FIG. 4 is a left side view of the portable air neck traction device for orthopedic purpose of FIG. 1;

FIG. 5 is a right side view of the portable air neck traction device for orthopedic purpose of FIG. 1;

FIG. 6 is a top plan view of the portable air neck traction device for orthopedic purpose of FIG. 1; and,

FIG. 7 is a bottom plan view of the portable air neck traction device for orthopedic purpose of FIG. 1.
